(57) CLAIM

The ornamental design for a container for game accessories as shown and described.

DESCRIPTION

FIG. 1 is a front, top, and first side perspective view of a container for game accessories embodying the new design; FIG. 2 is a back, bottom, and second side perspective view thereof;

FIG. 3 is a front view thereof;

FIG. 4 is a back view thereof;

FIG. 5 is a first side view thereof;

FIG. 6 is a second side view thereof;

FIG. 7 is a top view thereof; and,

FIG. 8 is a bottom view thereof.

The uniform repeating broken lines depict portions of a container for game accessories in which the claimed design is embodied and form no part of the claimed design.

1 Claim, 8 Drawing Sheets
